UNITED STATES PATENT OFFICE.

FRANK J. HEKRIDGE, OF DAVIDSON, SASKATCHEWAN, CANADA.

TABLE.

Application filed April 1, 1925, Serial No. 19,958.

To all whom it may concern:

Be it known that I, FRANK J. HEKRIDGE, a subject of the King of Great Britain, residing at Davidson, in the Province of Saskatchewan and Dominion of Canada, have invented new and useful Improvements in Tables, of which the following is a specification.

The object of this invention is to provide a leg support for tables of such construction that the same may be folded beneath the table top when not required for supporting the table, and whereby the said table presents a small and compact package for storage or for shipment.

A further object is to arrange on the under face of a table parallel flanges each provided with a slotted guide, and between these guides there is arranged a pair of bars, one of said bars having wheels or rollers on the ends thereof that are received in the guides, and both of the bars having hingedly connected thereto crossed legs which are pivotally associated and which have arranged therebetween breakable brace means and other non-breakable braces, the construction being such that the legs when folded together may be moved with the bars beneath the table, and the bar not provided with the wheels or rollers raised above the guides so that the legs may be folded against each other beneath the table top, and further wherein the breakable brace means are automatically brought into operative position when the bars and legs are moved to arrange the said legs in table supporting position.

A still further object is to provide a table top with foldable leg supports, in which the said legs are hingedly connected to bars that are movable on tracks between guideways on the bottom of the table, the rails of the track having their ends upset and rounded to limit the sliding movement of the bars when the legs are in folded or in table supporting positions, and to effect in holding the said legs in either of such positions.

The improvement consists in other objects and details of construction which will be fully set forth in the following description, illustrated by the accompanying drawings and pointed out with particularity in the appended claim.

In the drawings:

Figure 1 is a bottom plan view of the improvement in folded position.

Figure 2 is a sectional view on the line 2—2 of Figure 1.

Figure 3 is a sectional view on the line 3—3 of Figure 1.

Figure 4 is a perspective view of the support in set-up position.

Figure 5 is a sectional view on the line 5—5 of Figure 1.

Figure 6 is a perspective view to illustrate adjustable leg sections which may be employed.

Figure 7 is a fragmentary perspective view of one of the leg members to illustrate the eye carrying bracket thereon.

My improvement may be employed with equal success on either round top, square or rectangular tables. In each instance the table, on its under face, is provided with a pair of spaced flanges 1. On the inner face of each flange there is a channeled member 2 that provides a guide. The outer face of each of the channeled members is formed with a central opening 3.

At a suitable distance inward of the guides 2 there are secured metal plates 4 respectively. Each of these plates is of a length approximately equalling that of the guides 2, and each of the said plates has its end upset and rounded, as at 5. The plates 4 provide the rails of a track.

The numerals 6 and 7 designate rods which are round in cross section. Each of the rods is of a length equalling the distance between the guides 2, but the rod 7 has arranged on its ends preferably removable stub shafts 8 on which there are journaled wheels or rollers 9. The stub shafts pass through the openings 3 in the guides, and the wheels or rollers travel in the said guides. Each of the cross sectionally rounded bars is provided with continuous grooves or depressions 10, and the inner surfaces provided by the said depressions are arranged on the rails 4, the depressions being of a length corresponding to the width of the rails.

Outward of the depressions 10 each of the bars 6 and 7 is preferably formed with additional depressions in which there are received the rounded central portions of straps 11 whose ends are secured to leg members 12. The outer ends of the leg members are concaved to be received in the referred to depressions. In this manner it will be noted that the legs 12 are hingedly associated with the bars, and that the legs 12 on

the bar 6 are arranged to cross the legs on the bar 7. On the legs 12 there are secured angle brackets 13 each of which having one end formed with an eye 14. The eyes on the 5 cross legs are designed to align and to receive therethrough the ends of a rod 15. Passing through the ends of the rod 15 and contacting with the eyes 14 there are cotter pins. Preferably there is a washer or wear 10 plate on the rod between the cooperating eyes 14 of the brackets 13.

Between the cooperating pairs of crossed legs 12 there are pivotally secured links 16 which have their confronting ends pivotally 15 connected, as at 17, and one of the links at its said pivoted end is formed with a lip 18 to engage the second link when the links are arranged in parallelism. Also between one or both pair of the opposed legs 12 there 20 are cross braces 19.

If desired, the legs may be made up of adjustable sections as disclosed in Figure 6 of the drawings. In this instance the inner leg section carries guides 20 for the outer 25 leg section 21. The outer leg section is provided with an elongated slot 22 through which passes a bolt member 23 carried by the inner leg section. This bolt is engaged by a winged nut 24 which contacts with a 30 washer 25 arranged over the slot or opening 22.

In Figure 1 of the drawings, the legs are in folded position. The legs are drawn outwardly in the direction of the arrow A in 35 Figure 1. It should have been stated that the bar 6 overlies the bar 7 when the device is folded. The outward drawing of the legs will cause the bar 7 to engage with the rounded ends of the rails 4, limiting the 40 movement of the legs and bars in one direction. The bar 7 is held against the stops 5, and the bar 6 is then moved on the rails to bring the same to engage with the opposite 45 stops 5 on the said rails. This spreads the legs to arrange the same in set-up position,

as illustrated in Figure 4. The spreading of the legs automatically swings the brace links 16 into inter-locking engagement, so that the table is strongly and effectively supported. The parts are moved in an opposite direction to that just described in folding the legs beneath the table top, it being understood that the bar 6 simply travels between the guides and can be raised over the said guides to rest on the bar 7 50 when the legs are folded.

It is believed that the foregoing description, when read on the drawings will fully disclose my construction and its advantages, but it is to be understood that I am entitled 60 to such changes therefrom as fairly fall within the scope of what I claim.

It is, of course, obvious that one pair of legs may be of a less length than the other. This construction is especially desirable 65 when the table top is employed for drafting or like purposes where a slanting top is required. The rounded ends of the plates 4 are comparatively long, as by such arrangement the table may be lifted by grasping 70 the top thereof.

Having described the invention, I claim:—

A table top having depending flanges provided with channeled guides, a pair of bars 75 having their ends contacting the guides, trunnions on the ends of one of the bars received in the guides, wheels journaled on said trunnions, legs arranged in crossed pairs hingedly associated with the respective 80 bars, means pivotally connecting the respective pairs of crossed legs, rails on which the crossed bars travel when the legs are in set-up or are in folded position, and said rails having upset ends limiting the movement of the bars on the rails in both directions. 85

In testimony whereof I affix my signature.

FRANK J. HEKRDLE.
